UNITED STATES PATENT OFFICE.

HENRY P. ROBERTS, OF BOSTON, MASSACHUSETTS, ASSIGNOR TO SANITARY CIGAR CUTTER CO., A CORPORATION OF MASSACHUSETTS.

SANITARY CIGAR-CUTTER.

1,104,137.

Specification of Letters Patent.

Patented July 21, 1914.

Application filed October 15, 1913. Serial No. 795,267.

To all whom it may concern:

Be it known that I, HENRY P. ROBERTS, of Boston, in the county of Suffolk and State of Massachusetts, have invented certain new and useful Improvements in Sanitary Cigar-Cutters, of which the following is a specification.

This invention relates to an improvement in devices for cutting off the tips of cigars. Cigar cutters, as heretofore constructed, have been considered unsanitary for the reason that frequently a customer will place the tip of a cigar in his mouth preparatory to lighting the cigar, and will then remove it from his mouth and place it in the cutter to cut off the tip. Thus the opening in the cutting device into which the tip end of the cigar is inserted is a fertile source of infection by germs deposited thereon by the various customers using the device.

Accordingly, the primary object of the invention is to provide a device of the character described, which shall be sanitary. To this end, a strip of sanitary material, preferably thin paper so treated that it is transparent, is fed over the aperture into which the cigar tip is inserted, so that when the tip is inserted in the aperture and the cigar pressed down to cut off the tip it is surrounded by the paper which is pressed thereby into said aperture and against the edges thereof. Thus the paper is held between the cigar tip and the edge of the opening in the cutting device and the cigar is prevented from coming in contact with said aperture. When the cigar is removed and the device restored to normal condition, the paper is fed along so that a fresh portion is presented over said aperture for use with the next cigar.

The invention will be clearly understood from an inspection of the accompanying drawing, in which—

Figure 1 is a side-elevation of an illustrative embodiment of the invention, Fig. 2 is a right-hand end elevation, Fig. 3 is plan view, Fig. 4 is a longitudinal vertical section taken on the line 4—4 in Fig. 3, Fig. 5 is a transverse vertical section taken on the line 5—5 in Fig. 1, Figs. 6 and 7 are detail views of the spring sleeve, and Fig. 8 is a fragmentary sectional view showing the cigar tip in position to be cut off.

As illustrated in the drawing, the device comprises a base 10, having an inverted U-

shaped member 12 pivotally mounted at one end on a pintle 14, and having an aperture 16 in its upper wall near its other end adapted to receive the tip end of a cigar 17, as shown in Fig. 8. The member 12 is normally held in elevated position by a spring so that the former may be depressed in the act of cutting off the cigar tip, and returned to normal position by said spring, the upward movement being limited by a ledge 13 on said member engaging a ledge 15 on the base 10. In the present instance a leaf spring 18 is employed, which is fastened at one end to the base 10 and its other end is sharpened to form a knife edge 19 adapted to slide along the under side of the upper wall of the member 12 and sever the cigar tip when said member is pushed down. Instead of forming the knife and spring of one piece, I may employ separate elements to perform these functions.

Mounted at one end of the base 10 is a housing, preferably in the form of two cylindrical cup-shaped portions 20, 22, joined together where they meet, and also preferably reinforced by a bar 24 secured to their flat ends. This bar, together with the contiguous end walls of the casings 20, 22, forms a support for studs 26, 28, extending axially of said casings. A supply of paper 30 is carried by a spool 32, mounted on a sleeve 34, which is loosely mounted on the stud 26 and is provided with a flange 35 at one end adapted to form a head for one end of the spool 32. A coiled spring 36 surrounds the stud 26 and bears against the end wall of the casing 20 and against the end of the sleeve 34. A thumb nut 38 is threaded upon the outer end of the stud 26 and bears against the flange 35 to hold the roll of paper 30 in place, and also puts the spring 36 under tension so that the latter acts as a drag on said roll to prevent the same from unwinding except when the paper is drawn down, as will be hereinafter explained. A cover-plate 40 fits over the open end of the casing 20, and is provided with a central aperture through which the body of the thumb nut 38 projects.

The paper strip 30 passes from the supply roll through an aperture 40 in the side of the casing 20, then under a guard plate 42 which is hinged at one end to said casing, then over the upper surface of the member 12 and under a guide 44 carried by said

member, then over the aperture 16 and through a slot 46 in the end of the member 12, then through a slot 48 in the base 10, then through an opening 50 in the side of 5 the casing 22 to a take-up roll 52 to which it may be attached in any suitable manner.

The take-up roll 52 is provided with a sleeve 54 having fingers 55, which are deflected inward slightly to engage a barrel 56 with a slight degree of friction to permit relative slippage between the take-up roll 52 and said barrel when the paper is drawn taut by the feeding mechanism to prevent breakage of the web of paper. The barrel 56 is provided on one end with a flange 58, which forms a head for the take-up roll, and a ratchet wheel 60 is fast on said barrel. The barrel 56 is held in place on the stud 28 by a thumb nut 62 threaded 20 upon said stud and having its body portion extending through a cover-plate 64, by which the open end of the casing 22 is closed.

A feeding pawl 66 engages the teeth of the ratchet wheel 60 and is pivotally mounted 25 on one end of a lever 68, the other end of said lever being pivotally connected to one side of the member 12. The free end of the lever 68 is adapted to slide through an opening in the left hand end of the base 10 and 30 rest upon the wall of the base forming the bottom side of said opening, and the pawl 66 passes through an opening 70 in the side wall of the casing 22.

The operation of the device is as follows: 35 It being understood that the supply and take-up rolls are in place with the paper extending between them and over the aperture 16. The tip end of the cigar 17 is pressed down and with it the paper 30, as shown in Fig. 40 8, is pressed into the aperture 16 between the edges of the latter and the cigar tip, thus preventing said tip from coming in contact with the edges of said aperture. The downward pressure of the cigar causes 45 the member 12 to be swung downward into the dotted line position shown in Fig. 4, and the knife edge 19 moves past the aperture 16 to sever the cigar tip and also shears off the paper surrounding the same at the 50 under side of the member 12. During the downward movement of the member 12, while the cigar is in engagement with the paper web, the paper is drawn off from the supply roll 32, and is wound up on the take-up roll 52 by the engagement of the pawl 66 55 with the ratchet 60. When the cigar is re-

moved from the aperture 16, the member 12 is returned automatically to normal position by the spring 18, and said aperture comes under a fresh portion of the paper 60 preparatory for another cigar. The friction of the fingers 55 on the barrel 56 is sufficient to hold the take-up from turning backward during the upward movement of the member 12, yet this friction is merely 65 sufficient to enable the web to be wound up on the take-up by the pawl and ratchet, but allows relative slippage between said barrel and the sleeve 54 when the paper is taken up, thus preventing breakage of the web. 70 During the operation of the device the diameter of the supply on the roll 32 diminishes and the diameter of the roll on the take-up 52 increases, and when the diameter of the latter exceeds that of the former, 75 the latter would tend to wind up a greater amount than is fed from the supply and thus cause a breakage of the paper, if it were not for the slippage between said sleeve and barrel.

I claim:—

1. In a device of the character described, a pivotally mounted plate having an aperture adapted to receive the tip end of a cigar, a strip of paper extending over said aperture, means for severing the tip of the cigar, and means for feeding the paper forward to present a fresh portion over said aperture after each cigar tip is severed.

2. In a device of the character described, 90 a member having an aperture adapted to receive the tip end of a cigar, a strip of paper over said aperture, a take-up roll adapted to take up the paper as it is used, means for severing the cigar tip, and means for operating the take-up roll to cause said strip to move over said aperture to present a fresh portion over said aperture after each cigar tip is severed.

3. A device of the character described, 100 comprising a pivotally mounted member having an aperture adapted to receive the tip end of a cigar, a strip of paper fed from a supply and passing over said aperture, a take-up roll for taking up the web of paper, 105 means for cutting off the cigar tip, and means operative during the cutting operation for actuating the take-up roll.
